UNITED STATES PATENT OFFICE.

ALFRED E. JONES, OF NEWARK, ASSIGNOR TO SPAULDING, JENNINGS & CO.,
OF WEST BERGEN, NEW JERSEY.

MOLD FOR COMPOUND INGOTS.

SPECIFICATION forming part of Letters Patent No. 240,727, dated April 26, 1881.

Application filed December 17, 1880. (No model.)

To all whom it may concern:

Be it known that I, ALFRED E. JONES, of Newark, in the county of Essex and State of New Jersey, have invented an Improvement 5 in Molds for Compound Metal Ingots, of which the following is a specification.

Molds have been made in two or more parts for the reception of cast metal. In some instances one portion of the mold has been removed and another substituted, so as to leave the necessary space into which steel or other metal can be cast directly upon the iron. It is difficult to thus exchange parts of the molds while hot. In other instances a wedge-shaped filling-plate has been placed in the mold at one side, and the same has been withdrawn after the iron has been cast; but the space left for the steel is not parallel, and hence one part is thicker than the other, and owing to the unequal expansion of the metal-mold the said wedge is difficult to withdraw, and sometimes it becomes immovable.

My invention is made for avoiding the aforesaid difficulties; and it consists in combining 25 with the mold a peculiar hinged cover, that can be easily opened or closed, and a removable plate at the inside of the cover, so that after the iron has been cast into the mold the cover or side may be swung open sufficiently to remove 30 the pressure upon the inclosed plate, and then the plate removed and the cover or side replaced, and the steel cast into the parallel space that is thus left in the mold.

In the drawings, Figure 1 is a vertical section of the mold complete and ready for use. Fig. 2 represents the same as open for the removal of the plate. Fig. 3 is a section at the line $x-x$, and Fig. 4 is an edge view of the removable plate.

40 The mold is made with the three sides a, b , and c and bottom d either in one piece or firmly connected together. The foot or base of the mold extends, as at e , to form a hinge or bearing for the movable side or cover f to swing upon.

This cover is made with a recess for the reception of the movable plate g , and the edges of the cover f set closely against the edges of the mold. The lower part of the cover has a projection, i , that sets into the bearing e , forming with it an open hinge for the cover to swing 45 upon.

It is to be understood that the mold is closed and held by the movable ring l , and the plate g is in the cover. The iron is cast into the mold, and as soon as it is sufficiently consolidated 55 the ring l is lifted, the cover f swung back, and the plate g removed, and then the mold is closed again and the steel poured into the space previously occupied by the plate g , so that the two metals weld together. The plate 60 g should be provided with a hook, k , at the upper end, to sustain the plate in its proper position relatively to the cover.

The removable plate is to be parallel; but the same may be of any desired shape sectionally to form a bar or plate corresponding to the steel or other metal cast into the mold.

I claim as my invention—

1. The combination, with the mold $a b c d$, of a swinging cover, f , and the removable plate g , 70 for the purposes and as set forth.

2. The combination, with the mold $a b c d$, of the cover f , having the projection i , and the base e , forming an open hinge for the cover, substantially as set forth.

3. The combination, with a two-part mold capable of being opened and its removable rings, of a parallel plate or bar having a hook, k , for retaining it in position against one side of the mold, which plate is liberated by opening the mold, and is removed after one metal has been cast, substantially as set forth.

Signed by me this 11th day of December, 75
A. D. 1880.

ALFRED E. JONES.
